COMBINED SERVER AND CABINET

Harry S. Freiberg, Los Angeles, Calif.

Application February 21, 1955, Serial No. 34,616

Term of patent 14 years

(Cl. D33—19)

Fig. 1.

Fig. 2.

Fig. 3.

Fig. 1 is a front perspective view of a combined server and cabinet showing my new design;

Fig. 2 is an end elevation taken from the left of the combined server and cabinet as shown in Fig. 1 and illustrating the top in open position and with the handles omitted for convenience of illustration only; and

Fig. 3 is a front perspective view thereof similar to Fig. 1 but with the top open as in Fig. 2.

1 claim:

The ornamental design for a combined server and cabinet, as shown and described.
